PORTABLE DRIER

Charles V. Hallenbeck, Denver, Colo.

Application November 17, 1932, Serial No. 643,107

6 Claims. (Cl. 34—6)

This invention relates to driers such as are used for drying sand, gravel, or anything of a like nature and particularly driers which have a rotatable drum through which the material to be dried travels while the drying is being performed.

The general object of this invention is to provide a drier in the form of a small unit that can be readily transported, which drier shall have a large efficiency, large capacity and secure extreme heat for drying the material.

Another object of the present invention is to provide such a drier with a centrally disposed oil burner at the discharge end of the drier discharging flame and heat in a direction counter to the movement of the material being dried, the oil burner being so constructed that a flame will be discharged through nearly the entire length of the drier with an equal distribution of heat against the walls of the drier.

A still further object is to provide a drier so constructed that a central jet of unignited gas will be discharged from the burner into an auxiliary combustion chamber having outlets at intervals and having baffles tending to break the jet up, the burner being itself surrounded by a combustion chamber, thus permitting the front section of the drum to be completely enveloped in flame, the rear combustion chamber causing flames to be discharged which will fully heat the rear section of the drum.

Other objects have to do with the means for driving the drum and supporting it for rotary movement.

My invention is illustrated in the accompanying drawings, wherein:—

Figure 1 is a longitudinal section through the axial center of the drier;

Figure 2 is a transverse section on the line 2—2 of Figure 1;

Figure 3 is an elevation of the discharge end of the drier;

Figure 4 is an end elevation of the oil burner nozzle;

Figure 5 is a longitudinal section thereof.

Referring now particularly to Figures 1 and 2, 10 designates the base of any suitable supporting frame. Upon this base, the supporting framework 11 is disposed.

Carried upon this base, as will be later stated, 50 are a plurality of rollers 12, these rollers being supported on cross pieces 13. The drum 14 extends nearly the full length of the framework 11 and of the base and carries upon its exterior the tires 15 which may be of any suitable material.

55 The drum also carries upon its exterior the

peripheral gear ring 16 whereby the drum may be rotated as will be later explained. Surrounding the rear end of the drum is a dust chamber 19 which is, of course, fixed and within which the drum rotates. This dust chamber is formed to provide the discharge hopper 20 below the rear end of the drum and the chamber is connected by trunks 21 to a fan casing 22 from which a stack 23 extends. Within this fan casing are disposed the fans 24 mounted upon the shafts 25. Between the trunk 21 and the upper portion of the dust chamber 19 there are disposed the manually controllable valves 26, there being handles 27 whereby these valves may be manipulated. Preferably, there are two of these valves 26, each 70 hinged at its lower end and at its upper edge contacting with the stop 28. By operating these dampers or valves control may be secured of the withdrawal of dust by the fans 24.

When the dampers are entirely closed, no dust 75 will be drawn up through the stack 23 and, of course, when the dampers are fully opened, all of the dust will be taken out through the stack 23.

The hopper 20 is provided with a removable closure or gate 28a at its lower end through which 80 dust may be withdrawn from the hopper 20. The rear end of the drum 14 is convergently inclined as at 29, these convergent walls defining an opening 30. Disposed rearward of this opening 30 and extending downward through the rear end of the dust chamber 19 is a feed hopper 31 which opens into the rear end of the drum. The feed of material through this hopper is regulated by means of the rotatable, bladed element 32 which not only seals the inlet passage but acts to control the feed of material, this sealing element 32 being rotated by the discharge of material into the hopper.

At the forward or discharge end of the drum, there is disposed the circular refractory casing 33 which constitutes a main combustion chamber or fire box which is supported in position upon the frame 11 and enters the open forward end of the drum and is disposed concentrically thereto. Extending into this primary combustion chamber or fire box 33 and supported at the center thereof is the fuel pipe 34, the forward end of which is provided with the nozzle 35 shown in detail in Figures 4 and 5. This nozzle is hemispherical in form and provided with the central discharge opening 36 and a series of radially extending discharge slots 37. The central discharge opening discharges a very strong jet of gas axially of the drum and into an auxiliary combustion chamber 38 disposed longitudinally of the machine 105 110

and extending from the rear end of the drum toward the burner. This tubular combustion chamber is open at its opposite ends but at its rear end is provided with the conical baffle 39 5 shown in detail in Fig. 1.

The rear end of the combustion chamber 38 is flared at 40 and thus the conical baffle causes the products of combustion to be discharged divergently outward from the rear end of the combustion chamber. At intervals, the combustion chamber is provided with staggered outlet openings 41, the wall of the combustion chamber being outwardly deflected over those openings as at 42 and there being a baffle element 43 disposed inward of these openings and extending in the direction of the incoming jet, the wall 42 extending outward and rearward so that the heat and flame from the combustion chamber are directed outward and rearward counter to the direction of movement of the sand, gravel or other material being dried. The baffles 43 extend downward and forward toward the incoming jet for a purpose to be later stated. These outlets 41 are disposed at intervals along the entire length of the combustion chamber and are radially staggered with relation to each other so as to secure a uniform discharge of heat outward toward the walls of the drum. The slots 37 also discharge flames outward and rearward against the walls of the combustion chamber 33 but these flames are not projected with the force of the central blast.

The rear flared end of the combustion chamber carries a spider 44 upon which is mounted a plurality of rearwardly extending spirally disposed agitator blades 45, these blades extending into the feed hopper and acting to agitate material therein and prevent its clogging and also acting to feed the material forward as shown in Figure 1 into the drum. Also carried by the rear end of the combustion chamber are the inclined or curved blades 46 which act to stir the material at the rear end of the drier shell and convey it forward into the zone of action of the longitudinally extending stirring angle irons 47 shown in section in Figure 2 which are attached to the drum, extend radially inward therefrom and run the entire length of the drum.

Disposed between these angle irons are inclined inwardly extending plates or blades 47a which also act to stir up the material and feed it forward. Thus it will be seen that as the drum is rotated, the material will be fed little by little into the drum, carried around by the drum, submitted to the action of the heat discharged from the combustion chamber and from the openings 37 in the nozzle and gradually carried forward until it is discharged at the open forward end of the drum. Here the material is discharged downward into the elevator housing 48 from which it is carried by an endless bucket elevator 49 operating over the usual wheel 50 as illustrated in Figure 3. The material is guided into the housing 48 by the hopper 65.

The mechanism is driven in any suitable manner, but I have shown for this purpose a shaft 51 having a pulley 52 mounted thereon whereby power may be transmitted to the shaft. This shaft is operatively connected by any suitable means to the reducing gearing of any well-known character disposed at the middle of the drum and generally shown in Figure 1. This reducing gearing may include a shaft 53 carrying upon it a sprocket wheel 54 over which a sprocket chain 55 passes, this chain passing around an idler 56 and

then extending around the drum and engaging the sprocket ring or gear ring 18 in an obvious manner. The fans 24 are driven as shown in Figure 3 by sprocket chains or belts 57 and 58. The chain or belt 57 passes around a pulley or sprocket wheel 59 mounted on one shaft 25 and is crossed and passes over a pulley or sprocket wheel 60 mounted upon the other shaft 25. This last named shaft carries a pulley 61 over which the crossed belt 58 passes, this cross belt passing over a pulley 63 mounted on a shaft 64, which shaft is driven through the reducing gear A by any suitable gearing from the shaft 53. The crossed belt 58 passes over an idler pulley 66.

The drum is held from longitudinal movement with reference to the frame by means of the wheels 67 mounted upon the frame and engaging against the side faces of the tires 15. At the junction of the walls of the dust box and fan casing with the rotating drum, I have provided suitable sealing means indicated in Fig. 1 wherein 68 designates a wall of the dust box and 69 an angle iron attached to the wall of the drum and extending in the same direction as the wall 68. Any suitable packing may be disposed between the wall 68 and the flange or wall 69 and thus the drum may rotate within the dust box and yet all passage of dust from the dust box be prevented and the inlet of air to the dust box prevented.

The operation of the drier will be obvious from what has gone before. The material is fed into the hopper by any suitable means, causing the valve or gate seal 32 to partially rotate enough to let the material pass into the hopper below where it is slightly stirred by the screw constituted by the blades 45 before entering the drier drum. On entering the drier drum, the material is picked up by the blades 46 and advanced until the longitudinal angle irons or stirrers 47 engage it and carry it upwardly to the top of the drier shell 110 and then dropped. During this operation, it is subjected to the heat of the flames or products of combustion issuing from the nozzles or discharge openings of the combustion chamber 38.

The material is also being constantly advanced 115 by the diagonally positioned blades 47a and eventually the material is discharged from the forward end of the drum into the elevator.

The capacity of the drier may be regulated by inclining it from the feed end, permitting it to be readily discharged into the elevator. However, the material may be slowly advanced by means of the inclined plates 47a independently of any inclination of the drier drum. The fuel in the oil burner is under pressure sufficient to project a central 120 jet for a considerable distance into the drier and into the combustion chamber 38 from which the heat is diverted in all directions against the shell or drum. The fumes from the drier caused by combustion and by vapors discharged from the drying material are carried off mostly by the fans 24 and the stack 23. The dust settles in the hopper 20 and is taken out as desired. This dust may be discharged directly into a car or taken 125 away on a belt conveyor not shown. The exhausting means comprising the fans 24 with the dampers 26 may be so regulated as to take away surplus dust ahead of the drying action of the hot air from the burner. The fire tube or combustion chamber 38 and the combustion chamber 33 with the nozzle 35 are the important features of my invention. The central opening of the nozzle allows a heavy stream of oil to be projected into the combustion chamber, but this oil is not ignited 130

135

140

145

150

or burned until it reaches the combustion chamber.

It is to be particularly noted that the pipe 34 has a nozzle 35 thereon which is so perforated that a stream or jet of fuel is thrown axially through the center of the drum and into the auxiliary combustion chamber or tube 38; and that a spray from the radial slots in the nozzle is sprayed against the walls of the stationary combustion chamber 33. This spray ignites in the stationary combustion chamber 33 and the flame extends rearward through the drier drum as far as the auxiliary combustion chamber 38. The central stream or jet of fuel upon entering the auxiliary combustion chamber 38 is broken up by the pointed ends of the baffles 43 causing a live flame to continue for the full length of the drum, that is, for the full length of the combustion chamber 38. This construction causes combustion to occur immediately in the lateral or radial sprays of fuel but retards the combustion of the central stream of fuel until such time as the said central stream preheated by the heat in the forward portion of the drum is broken up by the baffles 43 and becomes ignited by coming in contact with the forward end of the metal tube 38 or auxiliary combustion chamber, which forward end has become highly heated by the heat of the flames discharged from the main combustion chamber 33 into the drum. By this method of heating the drum, I obtain practically the same result as would be obtained by placing one spray nozzle in the first fire box 33 and another spray nozzle in the center of the drum were such a thing possible but a feed pipe for a second spray nozzle in the center of the drum could not be run through the drying drum as the extreme heat developed would explode the fuel within the pipe.

It will be seen, therefore, that the basic feature of my invention is providing means by which fuel passes to the middle portion of the drum and is there broken up and ignited in an auxiliary combustion chamber. Thus both ends of the drier drum are enveloped in live flame giving extreme heat which greatly increases the efficiency of the apparatus. The stationary non-revolving combustion chamber 33 has an extension which keeps sand from falling into this stationary combustion chamber and forming a "glass" on the walls thereof.

It will be noted that the auxiliary combustion chamber 38 is set rearwardly in spaced relation to the main combustion chamber and does not interfere at all with the free and full ignition of the spray portion of the fuel, that is, that portion which is discharged from the radial apertures in the nozzle. These forward flames proceeding from the fire box 33 envelope the rear portion of the drum while the flames projected from the openings 42 cause the rear portion of the drum to be enveloped in flames.

It will be understood that the fuel projected from the pipe 34 and from the radial jets does not ignite until the fuel is sufficiently broken up to allow a sufficient amount of oxygen to mix with it. Therefore, the fuel must come into direct contact with some object before ignition can take place. Combustion chamber 33 is lined with fire brick which soon becomes of a white heat. The jets projected from the radial slots in the burner come in contact with this fire brick, are broken up and ignited and, as there is a very strong draft of air entering the fire box end of the drum and traveling through the drum toward the other end thereof, the fire and flame fill the drum back for

a distance of some six or eight feet, at which time the fuel is burned. The center stream or jet of atomized fuel and steam does not come in contact with any object until it enters the fire tube 38, at which time, the points of the baffles 43 begin breaking the fuel up. These points or baffles soon become white hot and break up and ignite the fuel as it passes through the fire tube 38, which, in turn, sends live flame outwardly through the louvres 41, thus filling the rear end of the drum with live flame. The live flame from the fire box 33 does not ignite the center stream or jet of fuel because the central stream at this point is not broken up and is, therefore, not mixed with oxygen and because it is traveling at such a high speed that it does not have time to get hot and break up from its internal combustion. The fire tube 38 must be made of an extremely high heat-resisting material. In actual practice, the material used is one which will stand a heat of 1800° F.

In starting a fire, when the drier is cold, a large block of wood or coal is placed in the combustion chamber 33 along with oil saturated waste. This is used to ignite the fuel from the slotted jets until such time as the brick lining becomes hot enough to ignite the fuel. The fire must continue to burn until the first point or baffle in the fire tube 38 becomes sufficiently hot to break up and ignite the fuel from the central stream. The baffles then become hot one after the other until all points or baffles in the fire tube are igniting the fuel. In actual practice, it takes a matter of about five minutes to bring the complete drum to full heat and secure complete combustion.

The supporting frame may be conveniently mounted upon a truck so as to provide a portable drier if desired.

While I have illustrated certain details of construction and arrangements of parts, it is to be understood that many minor modifications might be made in the details of construction without departing from the spirit of the invention as defined in the appended claims.

I claim:—

1. A drier of the character described including a drum open at its opposite ends, means for feeding material into one end of said drum as it is rotated, means for causing the material to feed along the drum as the drum is rotated to discharge material at the other end of the drum, a nozzle discharging a heating jet of combustible material axially through the central portion of the drum, the nozzle being located at one end of the drum, and a tubular combustion chamber extending axially of the drum and spaced from the nozzle and into which said jet is discharged and ignited.

2. A drier of the character described, including a drum open at its opposite ends, means for feeding material into one end of said drum as it is rotated, means for causing the material to feed along the drum as the drum is rotated to discharge material at the other end of the drum, a nozzle discharging a jet of combustible fluid axially through the drum, and a tubular combustion chamber spaced from the nozzle and extending axially of the drum into which said jet is discharged, the combustion chamber having discharge outlets at intervals along its length and disposed in a plurality of radially directed positions.

3. A drier of the character described including a drum open at its opposite ends, means for feeding material into one end of said drum and caus-

ing the material to feed along the drum to discharge material at the other end of the drum, a nozzle discharging jets of ignited combustible fluid toward the adjacent wall of the drum and discharging a heating jet axially through the central portion of the drum, the nozzle being located at one end, and a tubular combustion chamber extending axially of the drum into which said central jet is discharged, the combustion chamber having a plurality of outlet openings, the outer walls of which extend outward and rearward toward the inlet end of the drum.

4. A drier of the character described, comprising a supporting frame, a drum rotatably mounted upon the frame, the drum being open at its opposite ends, means for feeding material into the drum at one end thereof, means for causing the material to move along the drum toward the other end thereof as the drum is rotated, a burner nozzle extending into the forward end of the drum and discharging toward the feed end thereof, the burner nozzle having a central opening and a plurality of radially disposed slots, the nozzle being hemispherical whereby to discharge a central jet from the nozzle, and rearwardly and outwardly extending jets, a combustion chamber supported axially within the drum and into which the central jet is discharged, the combustion chamber having rearwardly directed openings, the rear end of the combustion chamber being flared and having a cone disposed therein.

5. A drier of the character described, including a rotatably supported drum, means for rotating the drum, the drum having an opening at its rear end, the walls of the opening being inwardly and

rearwardly directed, a feed hopper extending into the opening in the rear end of the drum, a burner extending axially into the opposite end of the drum and having a discharge nozzle formed with a central opening, a combustion chamber extending from the rear end of the drum toward the nozzle but having its forward end spaced from the nozzle, the jet discharged from the nozzle being discharged into said combustion chamber, the combustion chamber having a plurality of rearwardly and outwardly extending discharge openings, the rear end of the combustion chamber being flared and having a cone therein, and feeding means located at the rear end of the combustion chamber rearward of the cone.

6. A drier of the character described, including a drum, means for feeding material into one end of said drum and causing the material to feed along the drum to the discharge end thereof, a centrally disposed combustion chamber located at one end of the drum and opening toward the middle of the drum, a nozzle within the combustion chamber discharging jets of combustible fluid against the walls of the drum and discharging a central jet axially through the central portion of the drum, and a tubular combustion chamber spaced from the first named combustion chamber and extending axially of the drum into which said central jet is discharged, the combustion chamber having a plurality of outlet openings, the outer walls of which extend outward and rearward away from the first named combustion chamber, there being baffles carried by said combustion chamber extending inward thereof and toward the first named combustion chamber.
